UNITED STATES PATENT OFFICE

2,432,045

FLOAT OPERATED CIRCUIT CLOSER

Allan E. Sheldon, Yakima, Wash.

Application July 12, 1946, Serial No. 683,002

1 Claim. (Cl. 200—84)

1
This invention relates to a float operated circuit closer and has for its primary object to close a circuit and signal an approaching train should the right of way or track become inundated.

Another object is to close an electrical circuit through a signaling system when water rises along the right of way beyond a predetermined point.

The above and other objects may be attained by employing this invention which embodies among its features a float actuated lever, a latch adapted to be released by the lever when the float attains a predetermined height, a spring pressed closure normally restrained against movement under the influence of the spring by the latch, a pair of stationary contacts and a bridging contact carried by the lever and adapted to be moved into engagement with the stationary contacts when the latch has been released by a float.

In the drawings,

Figure 1 is a plan view of a portion of a railroad track showing my improved circuit closer mounted on a cross tie thereof,

Figure 2 is an enlarged sectional view through the circuit closer,

Figure 3 is a top plan view of the circuit closer showing the cover removed,

Figure 4 is a transverse sectional view taken substantially along the line 4—4 of Figure 2,

Figure 5 is a horizontal sectional view taken substantially along the line 5—5 of Figure 2,

Figure 6 is a perspective view of the push rod and bridging contact.

Figure 7 is a perspective view of the plunger and latch carried thereby, and

Figure 8 is a fragmentary side view of a modified form of bridging contact.

Referring to the drawings in detail a railroad track designated generally 10 is laid along a right of way and comprises the conventional rails 11 supported on conventional cross ties 12. One of the cross ties 13 is provided with an extension 14 upon which my improved circuit closer designated generally 15 is mounted. The circuit closer 15 above referred to comprises a substantially rectangular box-like case having a base plate 17, side and end walls 18 and 19 respectively and a removable cover 20. One of the end walls 19 is pierced to receive spaced insulating bushings 21 in which spaced contacts 22 are supported and from which lead suitable conductors 23 connected to any suitable signaling system (not shown).

Supported on the bottom wall 17 of the casing 15 is a pedestal 24 the upper end of which is pierced with a transverse opening for the recep-

tion of a pivot pin 25. A standard 26 projects upwardly from the base 24 in spaced parallel relation to the pedestal 24 and carries at its upper end a guide sleeve 27 the purpose of which will be more fully hereinafter be explained. The bore through the guide sleeve 27 extends perpendicular to the axis of the pivot pin 25 so that the push rod carrying the bridging contact will move longitudinally of the device.

10 Supported on suitable studs 28 which rise upwardly from the base 17 between the pedestal 24 and the standard 26 is a horizontally disposed guide plate 29 formed with an axial opening 30 in which a plunger rod 31 is mounted to slide. The lower end of the plunger rod is provided with a head 32, and mounted between the underside of the head 32 and the upper side of the base 17 between the supports 28 is a compression coil spring 33 which yieldingly urges the head 32 and plunger 31 upwardly. Secured to the extreme upper end of the plunger 31 is a latch plate 34 carrying at the end nearest the standard 26 a latch-dog 35 the purpose of which will be more fully herein-after explained.

25 25 Pivotedly mounted on the pivot 25 in the upper end of the pedestal 24 is a lever 36, one end of which carries a float 37 which normally rests on the bottom or base plate 17 as illustrated in Figure 2. The end of the lever 36 opposite the float 37 is provided with a pressure finger 38 which overlies the upper surface of the latch plate 34 adjacent the end opposite that carrying the latch-dog 35.

30 35 Mounted for longitudinal sliding movement in the bore of the sleeve 27 is a push rod 39 carrying at one end a keeper 40 for engagement behind the latch-dog 35, and carried at the opposite end of the push rod 39 is a bridging contact 41 which under certain circumstances to be more 40 fully hereinafter described engages the contacts 22 to establish electrical communication between the two. A compression coil spring 43 surrounds the push rod 39 between the bridging contact and the sleeve 27 so as normally to urge the bridging 45 contact into engagement with the contacts 22 to close the signaling circuit.

45 In the modification illustrated in Figure 8 I have shown a bridging contact which is adapted to be mounted on the end of the push rod 39 in place of the contact 41 and this bridging contact comprises a base plate 44 carrying on the face which faces the stationary contact a strip of insulating material 45 to which in turn, is attached adjacent opposite ends spaced conductor plates 46 each of which is provided adjacent op-

posite ends with a pad for engagement with a pair of stationary contacts carried by the end wall of the casing, when it is desired to control two separate signaling circuits. It will be understood of course, that the stationary contacts carried by the end wall of the casing are insulated therefrom in an approved manner, and are connected through suitable means to their respective signaling circuits.

In use, it will be understood that the unit 15 is attached to the extension 14 of a cross tie 13 of the railroad track as illustrated in Figure 1 at a point where inundation is likely to take place. Should water rise above the level of the cross ties 12 and 13 it will enter the casing through passages 47 formed in the bottom wall 17 and rising within the casing, will cause the float 37 to move upwardly so as to rock the lever 36 and move the finger 38 into contact with the latch plate 34, to depress the latter against the compression of the spring 33. Depression of the latch plate will cause the latch-dog 35 to be retracted from its position in engagement with the keeper plate 40 of the push rod 39 so as to allow the rod 39 and bridging contact 41 to advance under the influence of the spring 43 and move the bridging contact 41 into engagement with the stationary contacts 22, thus closing a signaling circuit so that a train approaching the inundated portion of the track may have advance warning of the condition. Should it be so desired, the entire unit may be enclosed in a fence (Fig. 1) which will protect it from injury by bodies floating in surrounding water.

While in the foregoing there has been shown and described the preferred embodiment of this invention it is to be understood that minor changes in the details of construction, combination and arrangement of parts may be resorted to without departing from the spirit and scope 40 of the invention as claimed.

I claim as my invention:

- A float operated circuit closing unit adapted to be mounted adjacent the right of way of a railroad for closing a signalling circuit when the right of way is inundated, which includes a base plate adapted to be mounted on a cross tie, a pedestal rising from the base plate, a lever rockably supported at the upper end of the pedestal, a float carried by one end of the lever and normally resting on the base plate, a guide plate supported in spaced parallel relation to the base plate near the end of the lever opposite the float, a plunger operable through the guide plate along an axis perpendicular to the base plate, a head at the upper end of the plunger adapted to bear against the underside of the lever adjacent the end opposite the float, a latch-dog projecting upwardly from the head, a standard rising from the base plate in spaced parallel relation to the pedestal, a sleeve carried by the upper end of the standard with its axis parallel to the plane of the base plate, a plunger rod slidable through the sleeve, a head on the plunger rod adapted to engage behind the latch-dog when the plunger rod is retracted, a spring urging the plunger to move against the restraint of the latch-dog, a wall at the end of the base near the standard, spaced contacts carried by the wall and a bridging contact carried by the plunger rod opposite the head and adapted to bridge the spaced contacts when the plunger rod is moved under the influence of the spring.

ALLAN E. SHELDON.
